Specification for Design.

Patented July 4, 1922.

Application filed July 6, 1921. Serial No. 482,849. Term of patent 14 years.

To all whom it may concern:

Be it known that I, ARTHUR A. FRANK, a citizen of the United States, residing at Milwaukee, in the county of Milwaukee and State of Wisconsin, have invented a new, original, and ornamental Design for Tires, of which the following is a specification; reference being had to the accompanying drawing whereof—

Figure 1 is a front view of the tire showing my new design, while

Figure 2 is a sectional view of the tire shown in Figure 1, taken on the line 2—2 of Figure 1.

I claim:

The ornamental design for a tire substantially as shown.

ARTHUR A. FRANK.
